(57) **CLAIM**

The ornamental design for a rifle scope as shown and described.

DESCRIPTION

FIG. 1 is a front, left and top perspective view of the first embodiment of a rifle scope, showing my design; FIG. 2 is a rear, right and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is an enlarged view of detail 11 in FIG. 2.

FIG. 12 is an enlarged view of detail 12 in FIG. 2.

FIG. 13 is a front, left and top perspective view of a second embodiment of a rifle scope.

FIG. 14 is a rear, right and bottom perspective view of the second embodiment of the rifle scope of FIG. 13.

FIG. 15 is a front elevation view of the second embodiment of the rifle scope of FIG. 13.

FIG. 16 is a rear elevation view of the second embodiment of the rifle scope of FIG. 13.

FIG. 17 is a left side elevation view of the second embodiment of the rifle scope of FIG. 13.

FIG. 18 is a right side elevation view of the second embodiment of the rifle scope of FIG. 13.

FIG. 19 is a top plan elevation view of the second embodiment of the rifle scope of FIG. 13.

FIG. 20 is a bottom plan elevation view of the second embodiment of the rifle scope of FIG. 13.

FIG. 21 is an enlarged view of detail 21 in FIG. 13.

FIG. 22 is an enlarged view of detail 22 in FIG. 14.

FIG. 23 is an enlarged view of detail 23 in FIG. 14; and, FIG. 24 is an enlarged view of detail 24 in FIG. 14.

The dashed broken lines depict portions of the rifle scope that form no part of the claimed design. The dot-dash broken

(Continued)

lines in FIGS. 1-2, 9-14, and 21-24 depict the boundaries of the enlargements that form no part of the claimed design.

1 Claim, 24 Drawing Sheets
